LINK REDUCING RECIPROCATING KNITTING ATTACHMENT

John Allen Yankeelov, Roselle, N. J., assignor to
Tisch Machine & Tool Company, Inc., Elizabeth, N. J.

Application January 16, 1948, Serial No. 2,735

5 Claims. (Cl. 66—86)

1

My invention pertains to knitting machines and more specifically to a method for controlling the pattern of material being knitted on a horizontal or vertical knitting machine.

The principal objective of my device was to provide a novel means whereby the number of links necessary to knit a certain pattern will be reduced to a minimum.

My device will also eliminate the necessity of providing pattern chains of excessive length in forming a solid knitting pattern.

The invention in its broadest aspects provides a mechanical clutch whose operation is determined by a novel pattern control mechanism. The clutch mechanism provides for a reciprocating movement which enables the use of two links to provide a solid design which in the normal procedure would require hundreds of links.

The advantages of such a link reducing system are many and it enables the operator to quickly and easily change his design pattern which normally required a large number of adjustments and consumed a great amount of time.

Further advantages and unique features of my invention will be apparent as I proceed with the description.

With reference to the drawings:

Figure 1 shows a front elevation partially in section of the clutch mechanism.

Figure 2 shows a front elevation of the cam that provides intermittent motion to the clutch mechanism.

Figure 3 shows a sectional view on line 3—3 of Figure 1.

Figure 4 shows a side elevation of a micro switch and its associated cams.

Figure 5 shows an end elevation of the bell crank and associated mechanism.

Figure 6 shows a front elevation of the bell crank and the block to which the solenoid operated pawl is attached.

Figure 7 shows a schematic wiring diagram of the pattern control mechanism.

Figure 8 shows a plan view of a section of film that controls the operation of the pattern mechanism.

Figure 9 shows a modification of the pattern control means.

Figure 10 shows an enlarged view of the knitted design; and,

Figure 11 shows a further modification of the pattern control means.

Essentially, my invention consists of a reciprocating clutch mechanism that may be attached to the conventional horizontal or vertical knitting machines and an associated pattern control means for determining the order of actuation of the clutch mechanism.

2

As shown in Figures 1 and 3, the clutch mechanism 20 is driven by a cam 21 that engages with the teeth of the gear 22 to provide an intermittent motion to the clutch mechanism 20. 5 The cam 21 is mounted on the main drive shaft 23 that is constantly revolving. Gear 22 is attached to one end of the shaft 24 and on the opposite end of this shaft is a bevel gear 25 that meshes with right and left bevel gears 26 and 27 respectively. The left bevel gear 27 is attached to one end of a hub 28 with a clutch member 29 being secured to the opposite end of the hub by pin 30. The hub 28 is free to rotate in the stationary bearing 31. The right bevel gear 26 is similarly arranged having a hub 32, free to rotate, in a stationary bearing 33 with a clutch member 34 secured to the opposite end of the hub 32. Although the hubs are free to rotate in the stationary bearings these bearings 10 also prevent any lateral movement of the clutch members 29 and 34.

The clutch member 29 is equipped with a plurality of pins 35 that are adapted to engage in the openings 36 of the complementary clutch member 37 that is secured to the shaft 40. Similarly, the clutch member 34 is equipped with openings 41 which are adapted to be engaged by the pins 42 which are mounted on its complementary clutch member 43 that is likewise secured to the shaft 40. As the shaft 23 rotates 15 through the cam 21 an intermittent motion will be transmitted to the bevel gear 25. The bevel gear 25 will cause gear 27 to rotate in a clockwise direction and gear 26 to rotate in a counter clockwise direction. Both the gears 26 and 27 20 and the clutch members 29 and 34 are free to rotate on the shaft 40.

On one end of the shaft 40 is a bevel gear 50 that engages with another bevel gear 51 that is secured to the shaft 52. The bevel gear 50 is 25 held in place through a stationary bearing 53 and a collar 54. The gear 50 and its hub 55 are splined to the shaft 40 to allow the free axial movement of the shaft 40 that takes place during the reciprocating motion of the clutch mechanism 45 20. The opposite of free end of the shaft 40 is secured to a plate 60 through bolt 61. The lower extremity of the plate 60 is secured to a block 62 to which is pivotally connected one end of the link 63. The opposite end of the link 63 is connected to a crank pin 64 which in turn is mounted on a shaft 65 to which is affixed a gear 66. As the gear 66 rotates the crank pin 64 causes the link 63 to reciprocate in opposite directions for each 180 degree movement of the pin. A spring 50 67 and ball 68 arrangement engages alternately in notches 69 located at the top and bottom of a collar 70 secured to the crank pin shaft 65 to

prevent any excessive movement of the pin 64 after each 180 degree movement. As can be seen, as the crank pin 64 causes a reciprocating motion of the link 63 the complementary clutch members 37 and 43 will alternately engage and disengage with their respective clutch members 29 and 34 causing the gear 50 to rotate first to the right and then to the left as a result of the intermittent motion provided by the cam 21, combined with the reciprocating motion described.

As shown in Figure 3, the gear 51 is connected to the shaft 52 at the opposite end of which is a sprocket gear 70 which drives a sprocket chain 71. The sprocket chain 71 in turn, drives a second sprocket gear 72 on shaft 73 which rotates the drum 74 on which are positioned a plurality of links 75. The links 75 in turn are equipped with pins 76 which are operated in the conventional manner to slidably move the thread guide bars of the conventional horizontal or vertical knitting machines.

As a result of the operation of the clutch mechanism 20 the shaft 73 will be given an oscillating motion which will cause a link 75 to be placed in position so that the thread bars may contact the pins 76. The first link 75 will then be moved out of position with a second link taking its place so that the thread bars may contact the pins of the second link. The oscillating motion will then bring the first link back in position so that the thread guide bars may once again engage the pins. Due to this oscillating motion the number of links needed to knit a certain pattern are substantially reduced.

As shown in Figures 5 and 6 the reciprocating motion is accomplished by movement of the bar 80 by the cam 81 which is positioned on the shaft 23. As the cam 81 engages the bar 80, as shown in Figure 1, the bell crank 82 which is pivoted at 83 will be operated. The short leg of the bell crank 82 is connected to the lower end of the bar 80 through link 84 while the longer leg of the bell crank 82 is connected to block 85 through link 86. The block 85 in turn is pivotally mounted on a shaft 87 so that it may rock back and forth when moved by the link 86. Mounted on the block 85 is an electrical solenoid 88 whose plunger 89 is connected to a pawl 90 through a link 91. When the solenoid 88 is energized the plunger 89 is caused to operate thereby pulling the pawl 90 into engagement with the ratchet 92. The ratchet 92 is secured to one end of shaft 87 while the gear 93 that engages with gear 66 is secured to the opposite end of the shaft. The pawl 90 has one end attached to a spring 94 which causes the pawl 90 to return to a normal position after the solenoid 88 has been de-energized. Likewise the bell crank 82 is attached to a spring 95 which pulls it back to a normal position when the bar 80 is not being contacted by the cam 81.

As the cam 81 rotates and contacts the bar 80 the bell crank 82 will pivot causing the link 86 to move the pivotal block 85. At the same time, the solenoid 88 will be energized causing the pawl 90 to engage in the ratchet 92. As the link 86 is moved by the bell crank 82 it will result in shaft 87 being rotated which in turn, rotates gear 93 that engages with gear 66 causing the crank pin 64 to rotate and thereby furnishing the reciprocating motion to the clutch mechanism 20.

When the solenoid 88 is de-energized the spring 94 will disengage the pawl 90 from the ratchet 92 and at the same time, the spring 95 will pull the bell crank 82 back into its normal position where

it will be ready to repeat the operation when the bar 80 is contacted by the cam 81.

Obviously, when the electrical solenoid 88 is de-energized no reciprocating motion will be transmitted to the clutch mechanism 20, and therefore, the clutch mechanism 20 will remain engaged in the position as shown in Figure 1, which will merely furnish an intermittent motion to the shaft 73 on which the drum 74 and links 75 are mounted. This intermittent motion will cause the links 75 and their pins 76 to be contacted in normal sequence to produce one pattern whereas when the oscillating or back and forth motion is given to the links, another pattern will be produced.

In Figure 7, I show a schematic wiring diagram of my preferred form of pattern control mechanism. The mechanism includes three micro switches, 100, 101 and 102 respectively, which are capable of being adjusted to either make or break an electrical circuit through the operation of their roller contact arms 103. Two of these micro switches 101 and 102 are operated by cams 104 and 105 positioned on the main drive shaft 23 with the result that on each revolution of the drive shaft 23 the cams 104 and 105 function to close the switch contacts. The micro switch 102 is connected in series with solenoid 106 whose plunger 107 is connected to a sprocket 108 on which is mounted a length of film 109. On each revolution of the drive shaft 23 the switch 102 will be closed resulting in the solenoid 106 being energized which in turn, will cause the plunger 107 to move the sprocket wheel 108 a short distance resulting in the film 109 being moved over the plate 110. A second electrical circuit consists of the switch 101 that is operated by cam 104 on the main drive shaft 23 which is connected in series with the solenoid 88 that actuates the pawl 90 and another micro switch 100 whose roller arm contacts 103 rides over the film 109 that is supported at this point by flat plate 110. The switch 100 is so arranged that its contacts are not closed until its roller arm 103 drops, which is in direct contrast to the operation of the other switches 101 and 102.

Shown in Figure 8 is a length of the film 109 with slots 111 in the center thereof. As the film 109 is moved under the roller of micro switch 100, the contacts of the switch will remain closed until that portion of the film 109 having the slot 111 reaches the roller 112. At that point, the roller 112 will drop in the slot 111 and ride on the plate 110 causing the contacts of switch 100 to close and thereby energizing the solenoid 88 that actuates the pawl 90. Obviously, when the roller 112 is riding in the slot 111, the pawl 90 will be actuated each time that the contacts on switch 101 are closed by the cam 104 on the main drive shaft 23. The film 109 is constantly being moved and when the end of the slot 111 is reached, the switch 100 will have its contacts opened once again and the pawl 90 will not operate. As it has been explained previously, the oscillating motion to the links is furnished only when the pawl 90 engages in the ratchet 92 and by making the slots 111 of various lengths, it can be seen that the design can be readily changed. The control circuit can be operated from the conventional 110 volts A. C. circuit.

In Figure 9, I show a further modification of my device in which all parts remain the same except for switch 100 which is replaced by a photo electric cell 120. Obviously, the same results will be achieved by placing the film 109 in such a

manner that the electrical circuit will be energized only when the light falling on the photo electric cell 120 passes through the slots 111 causing the solenoid 88 to be energized and the pawl 90 to operate.

In Figure 11, I show still a further modification in which switch 109 remains in the circuit, however, the film 109 has been replaced by a cam 130 which has a plurality of notches 131 spaced in its outer periphery. These notches 131 can be so placed in the cam 130 that the pawl 90 will be operated only when the cam 130 is in a predetermined position.

While the invention has been described in detail and with respect to a present preferred form which the invention may assume, it is not to be limited to such details and form since many changes and modifications may be made in the invention without departing from the spirit and scope of the invention in its broadest aspects. Hence it is desired to cover any and all forms and modifications of the invention which may come within the language or scope of any one or more of the appended claims.

I claim:

1. An improvement in knitting machines having revoluble pin links to be associated with thread guide bars which includes, a continuously driven drive shaft, a driven shaft associated with said pin links, connections between said shafts to intermittently turn the driven shaft in one direction or another including a reversing clutch mechanism associated with the driven shaft to reverse the intermittent motion thereof when operated, a linkage connected to said clutch mechanism, said linkage including a ratchet gear, a cyclically oscillated ratchet pawl operated from the drive shaft, a pattern control element operated cyclically from the drive shaft, and means associated with the pawl and operated by the pattern control element selectively to connect the pawl with the ratchet gear and operate the clutch mechanism.

2. An improvement in knitting machines having revoluble pin links to be associated with thread guide bars which includes, a continuously turning drive shaft, a driven shaft associated with said pin links, a bevel gear mechanism, means on the drive shaft to operate said bevel gear mechanism intermittently, said driven shaft being axially movable, a reversing clutch mechanism disposed between the bevel gear mechanism and the driven shaft, certain elements of said clutch mechanism mounted on and movable with said driven shaft, a linkage connected to said axially movable driven shaft, said linkage including a ratchet gear, a pawl mounted on an oscillatable plate and associated with said ratchet gear, a linkage connected to said plate and operated continuously from the drive shaft to oscillate said plate, a pattern control band, means associated with the drive shaft to cyclically move said band, means associated with said band and said pawl to selectively operate the pawl to engage the ratchet gear whereby said driven shaft is axially moved.

3. An improvement in knitting machines having revoluble pin links to be associated with thread guide bars which includes, a selectively slotted pattern control band, a continuously moving drive shaft, a driven shaft, means for intermittently operating the driven shaft in one direction or another from the drive shaft including a reversing clutch mechanism, and to axially

move said driven shaft to effect the reversal of its intermittent motion, an electrical switching means associated with the pattern band and with the clutch mechanism to selectively make said clutch mechanism effective and operate the clutch mechanism in one direction or another.

4. An improvement in knitting machines having revoluble pin links to be associated with thread guide bars which includes, a driven shaft 10 axially movable, a linkage adapted to be moved in one direction or another to axially move said driven shaft, said linkage including a ratchet gear, a driving shaft, a bevel gear mechanism connecting the driving and driven shafts, a pawl 15 associated with said ratchet gear, a linkage associated with said pawl and operated by said drive shaft to oscillate said pawl, a pattern band, and means associated between the pattern band and the pawl to operate said pawl selectively and engage it with the ratchet gear to axially move said driven shaft.
5. An improvement in knitting machines having revoluble pin links to be associated with thread guide bars which includes, a continuously 20 turning drive shaft, a driven shaft axially movable, a double bevel gear mechanism associated with the driven shaft and means on the drive shaft to intermittently operate said double bevel gear mechanism, a reversing clutch mechanism 25 connecting the bevel gear mechanism and the driven shaft, certain elements of the clutch mechanism on and movable with said driven shaft, said driven shaft being associated with said pin links, a linkage adapted to be reciprocated and connected to the driven shaft to move it axially in 30 one direction or the other, a ratchet gear included in said linkage, an oscillatable plate, a pawl on said plate associated with said ratchet gear, a solenoid on said plate connected to said pawl, a 35 cam on the drive shaft, a linkage associated with said cam and connected to said plate to oscillate the plate and the pawl thereon, a pattern control band having slots of selected length therein and at selected intervals 40 45 thereon, a cam on the drive shaft and circuit means including a switch operated by said last mentioned cam to cyclically step said band, another switch associated with the band and adapted to be operated by the encounter with a slot therein, another cam on the drive shaft and switching means on said last mentioned cam, circuit connections between the switching means and the switch on the band, and the solenoid to selectively operate the solenoid during the engagement of the switch on the band with a slot whereby the linkage to move the driven shaft axially is operated.
